HAIR CURLING DEVICE

Ruth Kahan Weaver and Paul T. Hahn, Chicago,
Ill., assignors to Gaylord Products, Incorporated,
Chicago, Ill., a corporation of Delaware

Application December 27, 1951, Serial No. 263,528

8 Claims. (Cl. 132—40)

1

This invention relates to methods and devices for curling and waving hair, and is more particularly concerned with cold permanent waving methods and devices useful in forming spirally wound curls commonly known and referred to as ringlets or pin curls.

It has heretofore been the practice in the art of permanent waving of hair by cold wave solutions to first saturate a tress of hair with the wave solution, then to wind the saturated tress of hair from its end inwardly toward the scalp around a cylindrical curling rod to form a Croquignole curl, then to apply a neutralizing solution to the tress of hair while the latter is in its wound condition on the Croquignole curler, then to remove the Croquignole curl from the curler and rinse the curl in clear warm water to remove the cold wave solution and neutralizer, and then to manually form the rinsed tress of hair into one or more pin curls which are secured flat against the scalp by hair pins, bobby pins, or other types of fasteners.

The present invention contemplates a method and device for cold permanent waving of hair in which a tress of hair is first spirally wound upon a ringlet curler to form a pin curl. While the pin curl is still in its wound condition on the curler, it is saturated with a cold wave solution, neutralized, rinsed and dried, thus effecting a material saving in time and labor.

This invention further contemplates the provision of a pin curl forming device on which a tress of hair may be spirally wound either from its end toward the scalp or from the scalp outwardly toward its end, after which the tress is locked in its wound condition upon the device and treated with solutions to form a permanent wave in the hair.

This invention further contemplates the provision of a pin curl forming device adapted to rapidly produce a uniform curl without injury to the hair.

Another object of this invention is to provide a ringlet type hair curler adapted to be snugly engaged against the scalp directly above the roots of a tress of hair wound upon the curler, the tress being preferably wound on the curler from the root outwardly to the extremity of the hair to form a flat dress curl, such as pin curls, finger curls, sculptor curls or ringlet curls. The use of the present hair curler eliminates the formation of "fish hooks" at the extremities of the hair caused by curling the tress inwardly from the ends toward the roots on "end curlers."

This invention further contemplates the pro-

2

vision of a hair curling device of skeletal construction adapted to permit the cold wave solution, neutralizer, and rinse water to permeate the innermost strands of the wound tress to obtain a complete saturation thereof.

It is a further object of this invention to provide a hair curling device embodying a skeletal spool upon which a tress of hair may be wound, and a skeletal cap to fit over and lock a wound tress upon the spool. By forming the spool and cap of lightweight material, such as a thermoplastic, it will be apparent that a large number of curlers may be applied to the hair of the user without causing discomfort.

15 This invention embodies other novel features, details of construction and arrangement of parts which are hereinafter set forth in the specification and claims and illustrated in the accompanying drawing, wherein:

20 Fig. 1 is a top plan view illustrating a hair curling device embodying features of the present invention.

Fig. 2 is a side elevational view of same.

Fig. 3 is a plan view showing the spool upon which a tress of hair is wound.

Fig. 4 is a side elevational view of same.

Fig. 5 is a sectional view taken along the line 5—5 of Fig. 3.

Fig. 6 is a top plan view showing the locking cap removed from the spool.

30 Fig. 7 is a side elevational view of same.

Fig. 8 is another side elevational view of the locking cap.

Referring now to the drawing for a better understanding of the present invention, the hair curling device is shown as comprising a spool 2 adapted to receive a spirally wound tress of hair, and a cap 3 adapted to be positioned upon and interlocked with the spool to secure the wound tress against displacement from the spool.

35 The spool 2 is of one-piece skeletal construction comprising a central ring-shape hub 4 joined to the medial portion of a plurality of circumferentially spaced, generally U-shape ribs 5 arranged to define an annular groove 6 to receive a wound tress of hair, the ribs being preferably arranged in pairs a, b, c, and d joined together at their ends at 7. Each pair of ribs a, b, c, and d is reinforced by means of an interconnecting portion 8 extending therebetween and joined thereto, and each set of ribs is joined to an adjacent set of ribs by means of braces 9 arranged on opposite sides of the hub 4. To facilitate winding a tress from its root end outwardly, one

45 50 55 of the braces 9 is omitted from each end of the

spool to provide unobstructed openings at 10 and 11 between the ends of two adjacent sets of ribs, as illustrated in Fig. 5.

The cap 3 is of one-piece skeletal construction embodying a plurality of arms 12 joined together at their inner ends at 13 and diverging outwardly and upwardly to merge with the upper portions of associated depending legs 14. As illustrated in Fig. 6, the legs 14 are arranged in diametrically opposed pairs diverging downwardly from their junctures with their related arms.

An upwardly projecting finger engaging portion 16 is provided above the juncture of each arm 12 with its associated leg 14 to facilitate mounting and removal of the cap relative to the spool. The lower extremity of each leg is formed with a relatively wide foot 17 having a protuberance 18 on its inner face for locking engagement under a brace 9 on the spool, and it will be noted that each foot extends below the adjacent end of the spool when the cap and spool are in assembled relation, as illustrated in Figs. 2 and 5.

In the use of the hair curling device shown and described, it will be noted that the ends of the spool 2 are identical in order that either end of the spool may be positioned against the scalp S to receive a wound tress of hair H and the locking cap 3, as illustrated in Fig. 5. It will also be noted that recesses 19 are formed in the hub 4 between adjacent ribs 5 to permit the passage of fluids to the innermost coil of a tress wound on the spool, and that the ends of each pair of ribs a, b, c, and d are formed with inwardly converging faces 20—20 to guide a tress of hair into the annular groove 6 during the winding operation.

As illustrated in Fig. 5, the device is adapted for use in forming cold permanent wave pin curls by first positioning the spool 2 against the scalp S, then inserting a tress of hair H through the opening 10 and winding the tress around the medial portion of the spool within the annular groove 6. The cap 3 is then mounted on the spool with the legs 14 straddling the wound tress of hair and is secured against accidental displacement therefrom by engagement of the protuberances 18 under the braces 9 adjacent the scalp. As the foot portion 17 of each leg extends below the end of the spool adjacent the scalp, mounting of the cap acts to move the spool away from the scalp, see Fig. 5, to facilitate subsequent operations.

After a tress of hair has been applied to the spool 2 and locked thereon by the cap 3, the hair is saturated with a cold permanent wave solution, then neutralized, rinsed and dried before removal from the curler. By forming the spool and cap of skeletal construction as herein shown and described, it will be noted that liquids and heated air are adapted to pass freely to all portions of a tress of hair wound within the groove of the spool. To provide a relatively strong, lightweight, inexpensive construction, the spool and cap are preferably molded from a suitable thermoplastic material.

While this invention has been shown in but one form it is obvious to those skilled in the art that it is not so limited but is susceptible of various changes and modifications without departing from the spirit and scope of the claimed invention.

We claim as our invention:

1. In a hair curler, a spool of one-piece skeletal construction including a plurality of generally U-shape ribs having medial portions radially disposed and circumferentially spaced about the

outer periphery of a narrow ring-shape hub to define an annular groove to receive a wound tress of hair, the medial portion of each rib being joined to said hub and spaced from adjacent ribs to define a plurality of circumferentially spaced axially extending recesses, said ribs being arranged in pairs having their adjacent ends joined together to define apertures for the passage of liquids and air.

10. 2. In a hair curler, a spool of one-piece skeletal construction including a plurality of generally U-

shape ribs having medial portions radially disposed and circumferentially spaced about the outer periphery of a narrow ring-shape hub to define an annular groove to receive a wound tress of hair, the medial portion of each rib being joined to said hub and spaced from adjacent ribs to define a plurality of circumferentially spaced axially extending recesses, said ribs being arranged in pairs having their adjacent ends joined together to define apertures for the passage of liquids and air, and braces joining adjacent pairs of ribs and defining with the hub a plurality of openings in registry with said recesses.

15. 3. In a hair curler, a spool of one-piece skeletal construction including a plurality of generally U-shape ribs having medial portions radially disposed and circumferentially spaced about the outer periphery of a narrow ring-shape hub to define an annular groove to receive a wound tress of hair, and a locking cap of one-piece skeletal construction including a plurality of circumferentially spaced legs to enclose the spool and engage a wound tress of hair within said groove.

20. 4. In a hair curler, a spool of one-piece skeletal construction including a plurality of generally U-shape ribs having medial portions radially disposed and circumferentially spaced about the outer periphery of a narrow ring-shape hub to define an annular groove to receive a wound tress of hair, the medial portion of each rib being joined to said hub and spaced from adjacent ribs to define a plurality of circumferentially spaced axially extending recesses, and a locking cap of one-piece skeletal construction including a plurality of circumferentially spaced legs to enclose the spool and engage a wound tress of hair within said groove.

25. 5. In a hair curler, a spool of one-piece skeletal construction including a plurality of generally U-shape ribs having medial portions radially disposed and circumferentially spaced about the outer periphery of a narrow ring-shape hub to define an annular groove to receive a wound tress of hair, the medial portion of each rib being joined to said hub and spaced from adjacent ribs to define a plurality of circumferentially spaced axially extending recesses, said ribs being arranged in pairs having their adjacent ends joined together to define apertures for the passage of liquids and air, and a locking cap of one-piece skeletal construction including a plurality of circumferentially spaced legs to enclose the spool and engage a wound tress of hair within said groove.

30. 6. In a hair curler, a spool of one-piece skeletal construction including a plurality of generally U-shape ribs having medial portions radially disposed and circumferentially spaced about the outer periphery of a narrow ring-shape hub to define an annular groove to receive a wound tress of hair, the medial portion of each rib being joined to said hub and spaced from adjacent ribs to define a plurality of circumferentially spaced axially extending recesses, said

ribs being arranged in pairs having their adjacent ends joined together to define apertures for the passage of liquids and air, braces joining adjacent pairs of ribs and defining with the hub a plurality of openings in registry with said recesses, and a locking cap of one-piece skeletal construction including a plurality of circumferentially spaced legs to enclose the spool and engage a wound tress of hair within said groove.

7. In a hair curler, a spool of one-piece skeletal construction including a plurality of generally U-shape ribs having medial portions radially disposed and circumferentially spaced about the outer periphery of a narrow ring-shape hub to define an annular groove to receive a wound tress of hair, the medial portion of each rib being joined to said hub and spaced from adjacent ribs to define a plurality of circumferentially spaced axially extending recesses, said ribs being arranged in pairs having their adjacent ends joined together to define apertures for the passage of liquids and air, braces joining adjacent pairs of ribs and defining with the hub a plurality of openings in registry with said recesses, and a locking cap of one-piece skeletal construction including a plurality of circumferentially spaced legs to enclose the spool and engage a wound tress of hair within said groove, said legs being formed with protuberances for interlocking engagement with said braces, and connected together at adjacent ends by radially disposed arms, said legs extending between adjacent pairs of ribs.

8. In a hair curler, a spool of one-piece skeletal construction including a plurality of generally U-shape ribs having medial portions radially

disposed and circumferentially spaced about the outer periphery of a narrow ring-shape hub to define an annular groove to receive a wound tress of hair, the medial portion of each rib being joined to said hub and spaced from adjacent ribs to define a plurality of circumferentially spaced axially extending recesses, said ribs being arranged in pairs having their adjacent ends joined together to define apertures for the passage of liquids and air, braces joining adjacent pairs of ribs and defining with the hub a plurality of openings in registry with said recesses, and a locking cap of one-piece skeletal construction including a plurality of circumferentially spaced legs to enclose the spool and engage a wound tress of hair within said groove, said legs being formed with protuberances for interlocking engagement with said braces, and connected together at adjacent ends by radially disposed arms, said legs extending between adjacent pairs of ribs.
